R. SAAS.
DRAFTING TRIANGLE.
APPLICATION FILED DEC. 18, 1909.

987,917.

Patented Mar. 28, 1911.

UNITED STATES PATENT OFFICE.

ROBERT SAAS, OF NEW YORK, N. Y.

DRAFTING-TRIANGLE.

987,917.

Specification of Letters Patent. Patented Mar. 28, 1911.

Application filed December 16, 1909. Serial No. 533,358.

To all whom it may concern:

Be it known that I, ROBERT SAAS, a subject of the King of Hungary, residing at New York, county of New York, and State 5 of New York, have invented certain new and useful Improvements in Drafting-Triangles, fully described and represented in the following specification and the accompanying drawings, forming a part of the 10 same.

This invention relates generally to improvements in drafting instruments, and particularly relates to a drafting triangle which is adjustable and so constructed that 15 it may be used on either side and lie flat on the surface on which employed and thus permit any degree or angle to be accurately laid out therewith.

A further object of the invention is to 20 provide such a triangle, the sides of which shall be so connected that they may be folded together so that the triangle when folded may be conveniently carried in the pocket of the coat or vest.

25 With these objects in view the triangle consists in certain constructions and arrangement of parts which are shown in the following drawings in which—

Figure 1 is a face view of the triangle, 30 the side forming the hypotenuse being shown in two different positions in full and dotted lines. Fig. 2 is an edge view looking to the right of Fig. 1. Fig. 3 is an edge view partly in section looking toward 35 the left of Fig. 1. Fig. 4 is a cross section on an enlarged scale taken on lines 4—4 of Fig. 1. Fig. 5 is an enlarged face view of the means employed for detachably securing the perpendicular side and the 40 base. Fig. 6 is a section taken on lines 6—6 of Fig. 5. Fig. 7 is a section taken on lines 7—7 of Fig. 6. Fig. 8 is a section similar to Fig. 6, the parts being separated. Fig. 9 is a cross section taken on lines 9—9 of 45 Fig. 1. Fig. 10 is a face view of the triangle showing it in its folded position.

Referring now to said drawings which 50 illustrate a preferred embodiment of the improved triangle, the triangle is shown as comprising a base 1, a perpendicular 2 and a hypotenuse 3. These parts or sides are connected together by suitable connections so that the hypotenuse is adjustable relatively to the base and perpendicular, and 55 the latter two sides detachably united so that when desired they may be separated

and the sides folded together. The sides are also formed and connected so that the outer edges of either the top and bottom surfaces of the sides, which edges form the 60 drawing edges, will lie flat on the drawing surface, there being no parts projecting above such surfaces which would prevent them from so lying, as shown in Figs. 2 and 3, the connections joining or uniting the sides 65 being either flush with such surfaces or within the plane thereof. The particular construction of the parts and connections may be somewhat varied. As shown the hypotenuse is slideable along the base 1, which 70 has one surface cut away as indicated by dotted line α Fig. 1, and which cut away part is provided with a slot 4, the sides of which are slightly beveled as indicated at 5. This slot forms a seat for a connection 75 indicated generally by 6 (Fig. 1) by which one end of the hypotenuse 3 is slidingly connected to the base. This end of the hypotenuse so connected to the base has one surface cut away so that it and the base will 80 overlap as shown in Fig. 3 and the hypotenuse may be slid along the base, following the dotted line α . The cut away portion on the hypotenuse is formed as shown in Fig. 1, so as to allow it to be freely slid 85 along the base as it assumes different positions relatively thereto. A further cut away portion 9 is also provided which may be provided with an indicating line 11, which may be brought into alignment with a degree scale 12 on the inner edge of the base at whatever angle the hypotenuse may be to the base, any desired degree or angle from 45° to 0° being thus easily ascertained. As 90 the hypotenuse is slid along the base from right to left, Fig. 1, it assumes a position approaching more and more to a vertical or perpendicular, rising from the base as it is so moved. Means are provided whereby 95 this movement is compensated for, which means may be somewhat varied. As illustrated, the end of the hypotenuse opposite that slidingly connected with the base, is provided with a cut-away portion 15, in which cut-away portion is a slot 16, in which 100 is adapted to work a stud 17 fast on the end of a connection 18, being secured thereto in any suitable manner. The slot extends through the hypotenuse and on the side opposite the cut-away portion 15 is beveled 105 and the stud 17 is beveled to correspond thereto, as shown at 19 (Fig. 9), the stud 110

being thus prevented from being pulled through the slot. The connection 18 at the end on which the stud is attached extends slightly beyond the slot and seats on the 5 cut away portion 15, as shown in Figs. 1 and 9. The other end of this connection 18 is rigidly secured to the upper end of the perpendicular 2 and is counter-sunk in such end so as to be flush with the surface thereof, as indicated in Fig. 9, being secured thereto by screws 18'.

Means are provided for securing the end of the hypotenuse 3 which slides in the base securely in position after it has been adjusted relatively thereto to obtain the desired angle. As shown, the connection 6 by which the hypotenuse is connected with the base as before referred to, comprises a square headed stud or hub 20, the head of this stud 20 being counter-sunk in the hypotenuse so as to be flush with the surface thereof, as shown in Fig. 4. This stud or hub is provided with a threaded shank 21, on which is secured a nut 22, this nut having beveled sides 23 which coöperate with the walls of the slot 4 before referred to. This nut when screwed tight holds the hypotenuse securely in position and is, as indicated (Fig. 4) slightly below the surface of the base. Means may be 20 provided for preventing accidental displacement of this nut, which means comprise a disk 24 apertured at 25 to receive a tool, which disk is adapted to be screwed on a threaded projection 26 on the end of the 35 hub or stud 20, and prevent the nut 22 from becoming displaced, this disk being flush with the surface of the base 1.

By loosening the nut 22 it is obvious that the hypotenuse of the triangle can be slid 40 along the base so as to form any desired angle from 45° to 90° on one side of a given perpendicular, and by reversing the triangle any angle from 45° to 90° may be produced on the other side of the perpendicular, the 45 sides and connections being arranged as described so as to leave no projecting parts and thus prevent the sides from lying flat on the drafting surface when so reversed. As before stated, one feature of the invention 50 is to provide a triangle of this kind which can be folded up, the base and perpendicular being detachably secured so that this can be done, and at the same time provide connections which will be flush with 55 the surfaces of the base and perpendicular on both sides so that the triangle will lie flat on the surface with which it is to be used on either side. It is further desirable that the means for detachably securing these 60 parts together be such that a rigid connection may be formed and one which will not give or yield during the act of using the triangle. These connections and means may be of any suitable character. In the particular construction illustrated, the end of the

base 1 and the contiguous end of the perpendicular 2 are cut away, as shown in Figs. 6 and 8 of the drawing so as to lap over on to each other and form a flush joint and the ends are rigidly and detachably secured 70 together by devices which will now be described.

Referring to Figs. 5 to 8, the cut-away portion on the perpendicular 2 has set in it so as to be flush therewith a plate 30, which 75 plate has riveted or otherwise fixedly secured therein a hub or stud 31, which is formed with a plurality of solid arms or wings 32, these arms or wings 32 being thus fixedly secured in the perpendicular 2. The base 1 80 has set into it so as to be flush with the surface thereof a fitting 33, which fitting is provided with as many slotted arms or wings 34 as there are solid arms 32, extending from a central portion 35 which surrounds the hub or stud 31, before referred to, on which the solid arms or wings 32 are carried. The solid arms 32 fit into and engage the slotted arms or wings 34 and the parts are thus held firmly against relative 85 movement. For positively holding the parts in their proper position, there is provided a thumb nut 36. This thumb nut is screwed into a threaded aperture provided in the hub or stud 31, before referred to, the head 90 of this thumb nut engaging the base 1, the fitting 33 and the hub or stud 31 and binding all the parts firmly together. When it is desired to fold up the instrument, the thumb nut 36 is loosened and the parts separated, 100 as shown in Fig. 8, the nut 24 being also loosened and the base 1 being lifted or raised slightly if necessary, and the legs of the triangle folded together, as shown in Fig. 10, when it may easily and conveniently be 105 carried in the pocket of a coat or vest.

As before referred to the base is provided with a degree scale 12, and may also be provided with an inch scale 40. It will be understood that these scales may be duplicated 110 on the other side of the base, for use when the triangle is used on the side opposite to that shown in Fig. 1. It is also understood that the specific construction of parts described may be varied and that the invention is not to be limited to such specific construction. 115

What is claimed is:—

1. In a drafting triangle, a base, a perpendicular detachably secured to the base, a 120 hypotenuse connected with the base and perpendicular and movable relatively thereto, and connections for connecting said sides together, said sides having their outer edges of substantially equal thickness and said connections being flush with the surfaces of said sides so that the triangle will lie flat on the drafting surface on either side. 125
2. In a drafting triangle, a base, a perpendicular detachably secured thereto, a hy- 130

potenuse slidingly connected to the base, said sides at their points of connection being cut away so as to over lap and form flush joints, and connections flush with the surfaces of the sides, so that the triangle will lie flat on the drafting surface on either side.

- 5 3. In a drafting triangle, a base, a perpendicular secured to the base, a hypotenuse connected at one end with the base so as to 10 slide thereon to form any angle between 45° and 90° and at the other end connected with the perpendicular so as to be movable relatively thereto, and connections flush with the surfaces of the sides for connecting the sides 15 together so that the triangle will lie flat on the drafting surface on either side.

- 15 4. In a drafting triangle, a base, a hypotenuse connected to the base so as to be movable thereon, a perpendicular provided with 20 a fitting having a plurality of projections, a fitting on the base having a plurality of sockets with which said projections co-act to hold the contiguous ends of the base and perpendicular rigidly together, said base, 25 perpendicular and fittings forming a smooth surface when united together.

- 25 5. In a drafting triangle, a base having one of its surfaces partially cut away longitudinally, a perpendicular secured to one end 30 of the base, a hypotenuse having one of its

surfaces at one end partially cut away and at that end overlapping on the cut away portion of the base and connections between the base and the hypotenuse co-acting with the walls of a slot in the cut away portion of 35 the base whereby the hypotenuse may be slid along the base to form any angle between 45° and 90° , and a connection between the hypotenuse and perpendicular and movable on one of them whereby the hypotenuse may be 40 moved relatively to the perpendicular, said connections being flush with the surfaces connected by them.

6. In a drafting triangle, a base, a perpendicular detachably secured to the base, a 45 hypotenuse connected at one end with the base so as to be slidable thereon from a position forming an angle of 45° to a position forming an angle of 90° and at the other end connected with the perpendicular so as to 50 be movable relatively thereto, and connections for connecting the sides flush with the surfaces thereof.

In testimony whereof, I have hereunto set my hand, in the presence of two subscribing 55 witnesses.

ROBERT SAAS.
